UNITED STATES PATENT OFFICE.

WALTER C. FELLOWS, OF PHILADELPHIA, PENNSYLVANIA, ASSIGNOR TO C. R. CARVER COMPANY, A CORPORATION OF PENNSYLVANIA.

DETACHABLE FEEDING TABLE FOR MACHINES.

Application filed June 18, 1926. Serial No. 116,816.

The object of my invention is to provide an adjustable work holding or feeding table, more particularly adapted for use with printing presses whereby the same may be readily detached and removed when for any reason access to the working parts of the press becomes necessary, and my improvements reside more particularly in the means employed for locking the removable table 10 in operative position.

In the practical application of my improvements in the preferred form, the press or machine is provided with two bracket devices spaced apart and each supporting a fixed table, said tables separated a suitable distance apart to permit ready access to the working parts of the machine, said space between the fixed tables being occupied by a removable table supported and positioned upon the brackets and detachably locked in such position by suitable locking means of specific form and constituting the essential part of my improvements.

My improved locking means comprises a vertical shaft journaled in the bracket and carrying at its upper end a lateral locking arm or heel extension, said shaft and arm movable downwardly under the influence of a spring, and said shaft having a lateral handle or lever portion by which it may be rocked whereby the lateral arm is adapted to yieldingly engage a keeper portion secured to the detachable table and thereby lock it in position.

My invention also comprehends details of construction which, together with the features above enumerated are more fully described hereinafter and more particularly pointed out in the claims.

Referring to the drawings: Fig. 1 is a plan view of a table structure embodying my improvements; Fig. 2 is a vertical section of the same on line 2—2 of Fig. 1; Fig. 3 is a transverse section on line 3—3 of Fig. 2; and Fig. 4 is a perspective view of a portion of the locking mechanism.

The printing press or machine proper is indicated in dotted lines at 2 and may be of any suitable construction. 3, 3, are two fixed tables arranged respectively at opposite sides of the machine leaving a gap or space 4 between them and by which access may be had to the printing press or other machine. 5 are brackets bolted at 6 to the main frame of the machine and each

presenting at the top two arms 7 and 8 respectively arranged at an angle to each other, the arms 8 being horizontal and projecting directly forward from the front of the machine, whereas the arms 7 project horizontally in a diagonal direction under the center of the table portions 3, 3, and to which said table portions are secured by screws 9. These bracket portions may be formed integral with the machine casting and I do not restrict myself in this respect to the manner in which they are formed or attached to the machine for which the table is adapted.

In this manner, the two tables 3, 3, are fixedly positioned and adapted to support the sheets or printed matter. 10 represents an intermediate table board removably secured in position between the two tables 3, 3. This table board 10 on its underside and adjacent to the right and left hand edges is provided with metal straps 11 which are secured in position by screws. The forwardly projecting portions 8 of the brackets 5 are made of a width sufficient to receive the strap portions 11 of the removable table board 10 and thereby sustain it against downward displacement, as will be clearly understood by reference to Fig. 2. The table adjacent to its sides is provided with pins 12 extending downwardly from the straps 11 and are received in holes 13 formed in the projecting portions 8 of the brackets 5, said pins definitely positioning the table upon its support so that it cannot be shifted forward or backward unless lifted so as to disengage the pins from the holes.

Each of the brackets 5 are provided with locking means, shown in detail in Fig. 2, for locking the table board 10 in position upon said brackets and intermediate of the fixed table portions 3, 3. As shown, the under adjacent edges of the table portions 3, 3, are provided with spacing straps 23 screwed in position and directly resting upon the forward projecting portions 8 of the brackets, whereby the upper surfaces of the table portions 3, 3, and the intermediate table board 10 are in proper alinement. The locking means for each of the brackets comprises a vertical shaft 14 journaled in a vertical bearing 17 in the bracket arm 8 and the upper portion of said shaft is provided with a head 15 having a lateral lock-

ing arm 16 formed on its under part with a beveled engaging surface 21 which, in locking position, extends over the edge of the strap 11 secured to the underside of the table board 10, (Fig. 2). The head 15 forms an annular collar portion which limits the downward movement of the shaft 14, so that the locking arm 16, when out of locking engagement, is sustained in such a manner that it may be readily moved over the rounded or beveled edge 22 of the strap 11. At the lower end of the shaft 14 is a collar 18 and which is secured to the shaft by a pin 19 driven through the collar and shaft 15 and extending laterally to constitute a handle or lever portion for rocking the shaft. Surrounding the shaft 14 and interposed between the collar 18 and the under portion of the part 8 of the bracket is a coil spring 20 the function of which is to firmly act upon the shaft to depress it and in that manner yieldingly force the locking arm 16 down upon the locking belt 11 of the removable table board 10. The strap 23 is suitably notched to provide a space 24 (Fig. 3) in which to position the head 15, and the under portion of the table part 3 is recessed as at 26 to provide a space in which the locking arm 16 of the shaft 14 may freely swing. Similarly, the under portion of the table board 10 is recessed as at 25 to permit movement of the end of the locking arm 16 and its engagement with the upper portion of the keeper or strap 11, all of which is clearly illustrated in Fig. 2.

From this explanation, it will be seen that the locking arm swings from above the strap 23 of the table portion 3 to the position above the strap 11 of the table board 10, with just enough spring action to maintain a yielding contact in its swinging motion and with force sufficient to hold the table board 10 firmly in position upon the bracket. The recess or pocket 26 in the table portion 3 is so shaped that the locking arm 16 can freely swing in one direction into and out of locking position, but cannot swing in the other direction, so that the shaft 14 rotating through an arc of ninety degrees will properly operate the locking arm 16 to bring it into either locking or unlocking position.

From Fig. 1 it will be seen that the levers or arms 19 of the two locks are directed toward each other when the locks are in locking positions and are, therefore, in position to be readily grasped by the operator and moved out of locking position with the levers or handles directed forward, said operation being capable of being readily performed without having to see the locks or the operating handles thereof.

The action of the spring 20, in addition to applying pressure to hold the table board 10 firmly in position and prevent all rattling, also performs the function of hold-

ing the locking devices in any positions of adjustment to which they may be moved. Consequently, when the locking devices are turned into unlocking positions for the purpose of removing the board 10, said parts 70 retain that definite position until the board is replaced, and, moreover, when the locking means are adjusted into unlocking positions, the levers or handles 19 are turned forward with an initial movement in the 75 same direction and, therefore, do not obstruct the operator in manipulation of the machine after the table board has been removed.

From the foregoing, it will be seen that so my improved locking means is self-adjusting and self-aligning, retains its positions for all adjustments, prevents rattling of parts, and compensates for wear, and its simplicity insures a long operative life without danger of getting out of order.

As shown in Fig. 1, the table board 10 is made U shaped so as to fit around the front and sides of the plunger of the press, but I do not restrict myself in this respect. 90 The three table parts 3, 10, 3 constitute, in effect, one continuous table when in use, but permits the intermediate part 10 to be readily disengaged from the permanently fixed parts 3, 3. It is manifest, however, that the part 10 may be used alone in association with the brackets, and if desired, may be extended laterally to any degree such as would be understood if the parts 3 were integral with the part 10 and merely rested 100 upon the arms 7 of the brackets 5 by omitting the screws 9, so that all of the said parts 3, 10, 3, would be removable as a unit. In other words, I do not restrict myself to the shape or size of the table board 10. 105

It will now be apparent that I have devised a novel and useful construction which embodies the features of advantage enumerated as desirable, and while I have in the present instance shown and described the 110 preferred embodiment thereof which has been found in practice to give satisfactory and reliable results, it is to be understood that I do not restrict myself to the details, as the same are susceptible of modification 115 in various particulars without departing from the spirit or scope of the invention.

Having now described my invention, what I claim and desire to secure by Letters Patent is:

1. The combination with a machine, of a feed table comprising brackets spaced apart, a detachable table board supported on both of the brackets, means for definitely positioning the table board upon the brackets, and separate locking devices secured to each of the brackets and adapted to engage the opposite side portions of the table board and clamp it down firmly upon the brackets and thereby prevent its rising and disengage- 130

ment from the means for positioning it upon the brackets.

2. The invention according to claim 1, wherein further, the locking devices have 5 their clamping means downwardly spring pressed.

3. The invention according to claim 1, wherein further, the locking means each 10 comprises a vertical rotary shaft having at the top a lateral locking arm for the table board and at the bottom lateral lever handle portions, and spring devices for yieldingly clamping the locking arms upon the table board.

15 4. The invention according to claim 1, wherein further, the locking devices each comprise a vertical shaft having a lateral locking arm at its top and a lateral lever handle at the bottom and said shaft journal- 20 ed in one of the brackets whereby the locking arm swings in a substantially horizontal plane, and a coil spring surrounding the shaft and having one end sustained by the bracket and the other end acting upon the 25 shaft to yieldingly force it downward whereby the clamping action is compensating and the locking means retains itself in any open or closed position in which it is placed.

5. The invention according to claim 1, 30 wherein further, the means for definitely positioning the table board upon the brackets comprise a vertical hole in each of the brackets and downwardly extending pins from the table board near its lateral edges and re- 35 spectively engaging the holes in the brackets.

6. The invention according to claim 1, wherein further, the locking means comprises rotary shaft members having engaging parts for locking the table member to the brackets, and a covering over the 40 engaging parts to shield them from above.

7. The invention according to claim 1, wherein further, there is provided on each side of the detachable table board a closely 45 associated fixed table secured to the respective brackets, said tables and table board having recessed under portions providing chambers covering the locking means and also providing spaces in which the engaging parts of the locking means are free to 50 operate.

8. The combination with a machine, of a feed table comprising brackets extending from the machine and spaced apart, a detachable table supported upon the brackets, and separate locking devices for detachably connecting the table to the brackets having manually operable parts arranged under the 55 table and accessible from the front thereof.

9. The invention according to claim 8, wherein further, the locking devices each comprise a rotary locking means having a handle portion and the handle portions directed toward each other when in locking 60 positions and whereby both are caused to be given an initial movement in the same direction when unlocking the table.

In testimony of which invention, I hereunto set my hand.

WALTER C. FELLOWS.
